SIGNAL SYSTEM

Filed Nov. 4, 1929

Inventor:
Lambert H. Lynn,
by *Charles E. Tulla*
His Attorney.

UNITED STATES PATENT OFFICE

LAMBERT H. LYNN, OF SCHENECTADY, NEW YORK, ASSIGNOR TO GENERAL ELECTRIC COMPANY, A CORPORATION OF NEW YORK

SIGNAL SYSTEM

Application filed November 4, 1929. Serial No. 404,722.

My invention relates to signal systems and more particularly to signal systems employing electron discharge devices.

It frequently becomes desirable in the use 5 of systems of the type indicated, to connect an electron discharge amplifier employing a single discharge device in the last stage to supply oscillations to an additional amplifier of push pull type or to other forms of balanced load circuits.

One of the objects of my invention is to provide improved means whereby this result may be effected.

A further object of my invention is to provide means whereby the potential on opposite sides of the load circuit of an electron discharge device employed as an amplifier is maintained in balanced relation with respect to the cathode. Thus, additional discharge 20 devices such as those of a balanced, or push pull amplifier, may be connected between the cathode and the opposite points on the load circuit and hence receive therefrom equal potentials which are in opposite phase. In 25 addition thereto the cathodes of all of the discharge devices may be maintained at a like potential and supplied from the same source.

A further object of my invention is to provide means such that when the coupling between amplifiers of the type mentioned comprises a tuned circuit, the tendency of parasitic oscillations to be set up in the tuned circuit due to unbalanced impedances between the opposite sides of the tuned circuit and 35 the cathode, resulting from inherent impedance of the discharge device, is avoided.

The novel features which I believe to be characteristic of my invention are set forth with particularity in the appended claims. 40 The invention itself, however, both as to its organization and method of operation together with further objects and advantages thereof, may best be understood by reference to the following description taken in connection with the accompanying drawing in which the single figure represents an embodiment of my invention.

Referring to the drawing, I have shown at 1 an electron discharge amplifier which 45 is connected to supply high frequency oscil-

lation to the grid of a pair of push pull connected amplifiers 2 and 3. Connected between the anode and the cathode of the discharge device 1 is a tuned circuit 4 comprising inductance 5 and a capacitance 6. The 55 cathodes of all of the discharge devices are maintained at ground potential and are connected to be supplied from a single source of electromotive force, this source comprising cathode heating transformer 7. An intermediate point on the tuned circuit 4 is similarly connected to the cathode, as indicated by the ground connection shown thereon. Opposite points on the inductance are connected through coupling condensers 8 and 60 9 to the grids of the discharge devices 2 and 3, respectively. Positive potential is supplied to the anode of the discharge device 1 through a circuit extending through the source of 65 anode potential 10 to a mid-point on the inductance 5, the upper terminal of which is connected to the anode. Positive potential is also supplied from the source 10 through a conductor 11 and an additional source of 70 potential 12 to the anode of the push pull 75 amplifiers 2 and 3, this connection being made to the mid-point on the primary winding of the output transformer 13. The usual sources of biasing potential 14 and 15 are connected between the cathode of the respective 80 amplifiers 1, 2 and 3 and the grids thereof, these connections being completed through the usual grid-leak resistances and grid inductance.

In operation oscillations are supplied 85 through input transformer 17 to the grid of discharge device 1 thereby to control the impedance of the discharge device. These oscillations are then excited, or repeated, in the tuned circuit 4, amplified by devices 2 and 90 3 and supplied to any desired output circuit through transformer 13. The output circuits of devices 2 and 3 may of course be tuned to the same frequency as circuit 4 or a multiple thereof as desired.

Referring now to the tuned circuit 4 which comprises the load circuit of the amplifier 1, the ground connection referred to is made up on the capacitance 6. This capacitance may 95 comprise a pair of condensers the movable 100

elements of which may be varied equally and in unison, the point on the circuit between the two condensers being connected to ground. In this way this capacitance is always maintained balanced with respect to the cathode.

It will be observed that the upper portion of the tuned circuit 4 is connected to the cathode through the space between the anode and the cathode within the envelope of the 10 electron discharge device. Where a three electrode electron discharge device is employed the capacity between these electrodes may be such as to have considerable effect upon the circuit 4. In systems employing an 15 electron discharge device of the screen grid type such as that indicated at 1 this capacity has less effect, but in this case an additional by-pass condenser 15 is connected between the screen grid and the cathode. This condenser has the same effect upon the tuned 20 circuit as the inherent capacity between the anode and cathode and, in fact, is effectively connected between the anode and cathode and may be treated as though it were inherent in 25 the discharge device. The effect of this capacitance will later be more fully understood.

For the purpose of overcoming the undesirable effects of this capacitance, a condenser 16 is inserted in the connection between the 30 cathode and the opposite side of tuned circuit 4. This condenser has a value such that it just balances the capacity between the opposite side of the tuned circuit and the cathode including the inherent capacity of the 35 discharge device. Thus the circuit 4 may then oscillate freely at a single frequency and in balanced relation with respect to the cathode. The grids of the discharge devices 2 and 3, the cathodes of which are connected 40 with the cathode of device 1, may then be connected through their respective coupling condensers 8 and 9 to opposite points on inductance 5 and hence receive from the tuned circuit oscillations of equal magnitude and 45 of opposite phase. Thus the amplifiers 2 and 3 may then operate in balanced relation and assume equal portions of the load.

It will now be apparent that the inherent capacity between the anode and cathode of 50 the discharge device 1 where a three-element electron discharge device is employed, and this capacity, in addition to the capacity 15 where a screened grid electron discharge device is employed, is effectively in shunt with 55 the upper portion of the capacitance 6. The effect of this, were condenser 16 not inserted in the circuit, is to cause the upper portion of the circuit 4 to be resonant at a frequency somewhat different from the frequency at 60 which the lower portion is resonant. As a result parasitic oscillations are likely to be set up in the opposite branches of the tuned circuit. While these parasitic oscillations are not likely to be particularly harmful when 65 the tuned circuit is adjusted to oscillate at

the lower frequencies it has been found that at extremely high frequency they may become so great as to cause the amplifier to become unstable or even inoperative.

Thus, the effect of the condenser 16, adjusted as set forth above, serves not only to cause the oscillations in the circuit 4 to be balanced with respect to the cathode and the amplifiers 2 and 3 to assume equal portions of the load, but it also has the important effect of stabilizing the amplifier 1 at the 70 higher frequency and preventing parasitic oscillations in the circuit 4.

While I have shown a particular embodiment of my invention, it will of course be understood that I do not wish to be limited thereto since other means of balancing the load circuit of an electron discharge device may be employed and, further, oscillations from this load circuit may be supplied to different types of circuits beyond the circuit 4. I, of course, contemplate by the appended claims to cover any such modifications of the arrangement shown as fall within the true 80 spirit and scope of my invention.

What I claim as new and desire to secure by Letters Patent of the United States is:

1. In combination, an electron discharge device having a grid, an anode, and a cathode, a load circuit connected between said anode and cathode, a connection between an intermediate point on said load circuit and said cathode and means for maintaining the potential on opposite sides of said load circuit in balanced relation with respect to said cathode, the side of said tuned circuit opposite said anode being effectively disconnected from said grid except through said anode and cathode.

2. In combination, an electron discharge device, having a grid, an anode, and a cathode, a tuned circuit connected between said anode and said cathode, a connection from an intermediate point on said tuned circuit to said cathode, and means connected between one side of said tuned circuit and the cathode to balance the impedance between the opposite side of said tuned circuit and said cathode, said one side of said tuned circuit being effectively disconnected from said grid except through said anode and cathode.

3. In combination, a pair of electron discharge devices connected in push pull relation, an input circuit connected between the grids of said discharge devices, an additional electron discharge device having an anode and a cathode connected respectively to one side and an intermediate point on said circuit, and a grid, a connection between the cathodes of all of said discharge devices and the mid-point on said circuit, and impedance means connected between the cathode and the side of said circuit opposite said anode, said opposite side of said tuned circuit being effectively disconnected from said grid except 120

through said anode and said cathode for causing the oscillations supplied by said circuit to said push pull electron discharge devices to be balanced with respect to said cathodes.

4. In combination, a pair of electron discharge devices connected in push pull relation, an input circuit connected between the grids of said discharge devices, an additional electron discharge device having an anode and a cathode connected respectively to one side and an intermediate point on said input circuit, and a grid, a connection between the cathodes of all of said discharge devices and a mid-point on said input circuit, and a condenser included in the connection between the cathode of said additional discharge device and the side of said tuned circuit opposite said anode, said condenser having capacity substantially equal to the effective capacity between the anode and the cathode of the discharge device, and said side of said tuned circuit to which said condenser is connected being effectively disconnected from said grid.

5. In combination, an electron discharge device having an anode, and a cathode, an output circuit having opposite sides balanced with respect to ground, a tuned circuit comprising shunt connected inductance and capacity, the sides of said output circuit being connected to opposite points on said tuned circuit, a source of electromotive force connected between said cathode and an intermediate point on said inductance, a connection between the midpoint on said capacitance and ground, a connection from one side of the tuned circuit to said anode and a condenser connected between the opposite side of said tuned circuit and ground, said condenser being of such value that the opposite sides of the tuned circuit are balanced with respect to ground and a parasitic path is produced from the cathode to the midpoint of said tuned circuit having impedance equal to the impedance of the opposite corresponding path including the anode of the discharge device.

6. In combination, an electron discharge device having an anode and a cathode, a control grid and a screening grid interposed between the anode and control grid, a condenser connected between said screening grid and cathode, a tuned circuit, one side of said tuned circuit being connected to the anode, the opposite side of said tuned circuit being connected to the cathode through a condenser, and the midpoint on said tuned circuit being connected to said cathode, and a balanced load circuit having opposite sides connected to points on said tuned circuit equally and oppositely spaced from said midpoint, said last mentioned condenser having a value substantially equal to the effective capacitance between said anode and cathode, said effective capacitance including the capacitance of said first mentioned condenser.

7. In combination, a pair of electron discharge devices connected in push pull relation, each of said discharge devices having a grid, an additional discharge device having an anode and cathode, an inductance and a condenser connected in series between said anode and cathode, the midpoint on said inductance being connected to the cathode and opposite points on said inductance being connected to said grids, and a tuning capacitance connected across said inductance having its midpoint connected to said cathode, said first mentioned condenser having capacitance equal to the effective capacitance between said anode and cathode whereby said opposite points may be maintained in balance relation with respect to said cathode.

In witness whereof, I have hereunto set my hand this 1st day of November, 1929.

LAMBERT H. LYNN.
